UNITED STATES PATENT OFFICE

108,587

DESIGN FOR A TEXTILE FABRIC OR SIMILAR ARTICLE

Abe Tillman, New York, N. Y.

Application November 24, 1937, Serial No. 73,153

Term of patent 3½ years

To all whom it may concern:

Be it known that I, Abe Tillman, a citizen of the United States of America, residing in city of New York, county of New York, and State of New York, have invented a new, original, and ornamental Design for a Textile Fabric or Similar Article, of which the following is a specification, reference being had to the accompanying drawing, forming part thereof.

The figure in the drawing is a plan view of a textile fabric or similar article showing my new design.

The design is characterized by the specific arrangement of the fringed blocks as shown.

I claim:

The ornamental design for a textile fabric or similar article, substantially as shown and described.

ABE TILLMAN.
